UNITED STATES PATENT OFFICE.

ALBERT L. RADLEIN AND GUSTAF SELANDER, OF CHICAGO, ILLINOIS.

ROTARY POLISHING-BRUSH.

1,141,143.

Specification of Letters Patent.

Patented June 1, 1915.

Application filed June 17, 1914. Serial No. 845,534.

To all whom it may concern:

Be it known that we, ALBERT L. RADLEIN and GUSTAF SELANDER, citizens of the United States of America, and residents of 5 Chicago, in the county of Cook, State of Illinois, have invented certain new and useful Improvements in Rotary Polishing-Brushes, of which the following is a specification.

10 This invention relates to that class of rotary polishing wheels or brushes used in the metal polishing trade in which the polishing portion is formed by a disk like pad of woven fabric mounted on a central carrying hub. And the present improvement has for its object to provide a simple 15 and efficient structural arrangement and combination of a series of woven fabric disks whereby the required diameter for effective polishing action is attained with a series of smaller disks, and by means of 20 which the ordinary polishing disks when worn down to an inefficient size for practical use in the ordinary way can be utilized 25 for further and effective work, all as will hereinafter more fully appear.

In the accompanying drawing: Figure 1, is a section on line $x-x$, Fig. 2, of a polishing wheel or brush embodying the present 30 invention. Fig. 2, is an elevation of the same.

Similar reference numerals indicate like parts in both views.

Referring to the drawings, 1 and 2, represented a pair of companion hub sections or members disposed in spaced relation to each other and formed with central orifices adapted to fit a power driven carrying arbor and be held thereby in proper longitudinal 40 alinement, as well as driven by the same.

3 represents a circular cluster of intermediate studs or pins extending between the spaced hub sections 1, 2, aforesaid. Said carrying studs 3 are preferably attached at 45 one end in any usual and suitable manner in one of the aforesaid hub sections, with their opposite ends adapted to engage in recesses formed therefor in the other hub section, as illustrated in Fig. 1.

50 4 represent a plurality of disks of woven

fabric, such for instance as what is known to the trade as "cotton duck," and which are of a small diameter as compared to that of the disks ordinarily used and required in metal polishing operations. As usual in 55 the present type of polishing wheels or brushes, the disks 4 will be built up to the required thickness of layers of woven fabric stitched together as shown. In the present invention the woven fabric disks 4, are 60 eccentrically mounted on the hub sections 1, 2, by orifices near their margins. Such orifices in turn have holding engagement with the circular series of holding studs or pins 3, above described, and the construction 65 is such that a series of the woven fabric disks 4, will form a circular cluster around the central carrying hub sections 1, 2, as illustrated in Fig. 2. The required width of the polishing face or perimeter of the 70 present wheel or brush, is attained by placing side by side the required number of the above described circular cluster of woven fabric disks 4, and in the preferred form of the present invention, each alternate cluster 75 of woven fabric disks 4, will have a staggered relation to the next adjacent cluster, with a view to attain an approximately continuous perimeter in the completed article.

5 is a laterally extending sleeve on the hub 80 section or member 1, and adapted to house the projecting ends of the studs or pins 3, and prevent injury to the operator in actual use.

Having thus fully described our said invention what we claim as new and desire to secure by Letters Patent, is:—

1. A rotary polishing brush comprising, a central hub member, a cluster of woven fabric disks associated with said hub member, and a series of holding studs carried by said hub member with a plurality of said holding studs passing through eccentrically located orifices in each disk of the cluster, substantially as set forth. 95

2. A carrying hub for rotary polishing brushes of the class described, the same comprising a pair of hub sections associated in spaced relation, a cluster of intermediate studs secured at one end to one of said hub 100

sections and passing loosely through orifices formed therefor in the other hub section, and a laterally extending sleeve associated with the last mentioned hub section and
5 adapted to house the laterally projecting ends of the aforesaid studs, substantially as set forth.

Signed at Chicago, Illinois, this 13th day of June, 1914.

ALBERT L. RADLEIN.
GUSTAF SELANDER.
